UNITED STATES PATENT OFFICE

2,475,885

WINDOW

Emil K. Geyser, Pittsburgh, Pa., assignor to E. K. Geyser Company, a corporation of Pennsylvania

Application June 6, 1945, Serial No. 597,866

9 Claims. (Cl. 169—75)

1

This invention relates to windows, and more particularly to those having metal frames.

It is among the objects of this invention to provide a window in which there are vertical metal bars between the opposite sides of the frame that are quickly and easily fastened in place without the use of separate fastening members; in which trim strips around the frame are locked in place by concealed fasteners; and in which the strip-retaining members also serve to hold the window frame in position in the window opening.

In accordance with this invention the top and bottom members of a metal window frame are provided with a plurality of transverse slots 15 spaced lengthwise thereof. Laterally spaced vertical metal bars that are wider than the length of the slots have reduced upper end portions that extend through the frame slots. These reduced ends are provided with lateral slits which form tongues that are bent laterally over the frame to lock the bars therein. In front of the bars the frame is provided with an inwardly opening channel for receiving the edges of window glass, and at the sides and along the top of the frame are trim strips the inner edges of which overlap the front of the frame. Each strip has a rearwardly extending projection opposite the channel web, and the latter is provided with an opening through which a screw extends. The outer end of the screw engages the trim projection to hold the strip in place. Preferably, the screw is loosely disposed in the web opening but is threaded in a separate retaining member that is pressed by the screw against the outside of the frame. The outer end of this retaining member may overlap another projection on the trim strip to clamp it against the frame. The inner end of the retaining member, in cooperation with an outwardly projecting flange on the window frame, clamps the frame to a supporting member secured to the building wall.

The preferred embodiment of the invention is illustrated in the accompanying drawings in which Fig. 1 is a fragmentary front view of a window; Figs. 2, 3, and 4 are transverse sections taken on the lines II—II, III—III, and IV—IV, respectively, of Fig. 1; Fig. 5 is a fragmentary horizontal section taken on the line V—V of Fig. 2; Fig. 6 is a perspective view of the upper end of one of the vertical metal bars; and Fig. 7 is an enlarged fragmentary section, taken from Fig. 2.

Referring to the drawings, a rectangular window opening is formed in the wall of a building which may be constructed from any suitable

2

building material. In the case of a brick wall, metal channels 2 are fastened by bolts 3 to the masonry forming the window opening in order to form a support to which a window frame can be attached. The front flanges 4 of these channels project into the opening considerably farther than their rear flanges 5 for a purpose that will be made apparent later.

The window frame that is set in this window opening is formed from head and sill members 7 and 8 joined by vertical members 9 all welded or otherwise fastened together rigidly at their ends. As shown in Figs. 2, 4, and 5, the head and sill are provided on their outer surfaces with pairs of integral parallel ribs 11 extending lengthwise thereof and having transversely inclined outer surfaces. These same members are provided at longitudinally spaced intervals with transverse vertical slots 12 (Fig. 5) extending through them and their ribs. The spacing of the slots is determined by the number of sections into which the glass is to be divided lengthwise of the window. The opposite ends of vertical metal bars 13 are reduced in width (Fig. 6) and extend through these slots which are shorter than the width of the main body of the bars so that the bars will project laterally beyond the ends of the slots and bear against the inner faces of the head and sill. The narrow ends of the bars are provided with lateral slits 14 that form tongues 15 the outer end portions of which originally are free of the ribs. When these tongues are bent laterally into engagement with the inclined surfaces of the ribs they draw the wider parts of the bars tightly against the opposite side of the adjoining frame members to lock the bars in the frame.

This rigid window frame is set in the window opening by first tilting the frame and inserting its bottom in the opening from the rear. As shown in Fig. 4, the sill has a depending forwardly inclined flange 17 that slips over the front flange 4 of the lower channel, and also a rear flange 18 formed to rest on top of and against the back of the channel's rear flange 5. The rest of the frame then can be swung forward into the window opening because the outside front flanges 19 with which it is provided will pass the narrow rear flanges of the adjacent channels and strike against the wide front flanges 4. The head and side frame members also are provided with rear flanges 20 which engage the back of the rear flanges of the channels.

The inside of the window frame is provided at its front with an inwardly opening channel 21 for

receiving the edges of panes of glass 22. The vertical joint between adjacent panes may be covered by a facing strip 23 (Fig. 1) held in place in any suitable manner. The channel 21 at the top and sides of the frame is provided with a series of laterally spaced openings 24 for receiving screws 25 by which trim strips are held in place. The trim strips 27 cover the space between the frame and the adjacent wall of the window opening at its top and sides. Thus, the 10 inner edge of each strip overlies and engages the front of one of the frame members from which it extends outwardly to a point close to the wall. The space between the wall and the trim strip is filled with caulking compound 28 to seal it. The rear surface of each trim strip is provided with a rib 29 that extends along the outer surface of the adjoining frame member to limit the extent that the strip can overlap the frame. This rib 15 also serves as a means for holding the strip in position. Thus, each screw 25 is threaded in an L-shape retaining member or clip 31 the outer end of which is provided with a notch 32 that receives the trim strip rib 29. As shown in Fig. 7, the outer surface of the rib, which is the surface closest to wall, is inclined outwardly away from its base toward that wall, and the adjoining surface of the notch is inclined in the same direction, so that when the clip is drawn against the frame the rib can not pull away from it. At the same time the wedging action caused by the pressure of the inclined surfaces of the clip and rib against each other draws the strip tightly against the front of the frame.

To hold the outer edge of each trim strip rigidly in place, it is provided with a rearwardly projecting flange 33 that bears against the front flange 4 of the adjoining wall channel 2. The trim strip flange is pressed against the channel by the inner ends of screws 25 which engage an inwardly and rearwardly inclined front surface of a rib 34 with which the trim flange is provided. The screws exert a wedging action on this rib that presses it backwardly. The inner ends of the clips bear against front flanges 4 of wall channels 2 and thereby lock the window frame in the window opening.

After the trim strips have been placed in position and the screws have been tightened, putty 36 is packed in frame channels 21 and the window panes 22 are inserted in them. Thus, screws 25 not only are hidden from view, but they are completely protected from the weather. No fastening members for the frame or the trim strips are visible.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. In a window, a frame provided with an inwardly opening channel for receiving the edge of a pane of glass, the web of said channel having an opening through it, a trim strip substantially L-shape in section extending along the outside of the frame with its inner edge engaging the front of the frame, said strip having a rearwardly extending flange opposite said opening, said flange being provided with an integral member projecting toward said opening and a

screw in said opening with its outer end engaging the front surface of said member to hold the trim strip in place.

2. In a window, a frame provided with an inwardly opening channel for receiving the edge of a pane of glass, the web of said channel having an opening through it, a trim strip extending along the outside of the frame with its inner edge engaging the front of the frame, said strip having a rearwardly extending member opposite said opening provided with an outwardly and forwardly inclined surface, and a screw in said opening with its outer end pressing against said surface to wedge said strip rearwardly.

3. In a window, a frame provided with an inwardly opening channel for receiving the edge of a pane of glass, the web of said channel having an opening through it, a trim strip extending along the outside of the frame with its inner edge engaging the front of the frame, said strip having a projection engaging the outer surface of the frame and also having a rearwardly extending member opposite said opening, locking means engaging the outside of said web and overlying said projection, said means being provided with a threaded hole registering with said opening, and a screw in said web opening threaded in said hole with its outer end engaging said member to hold the strip in place.

4. In a window, a frame provided with an inwardly opening channel for receiving the edge of a pane of glass, the web of said channel having an opening through it, a trim strip extending along the outside of the frame with its inner edge engaging the outer front edge of the frame, said strip having a projection engaging the outer surface of the frame and also having a rearwardly extending member opposite said opening, a locking element engaging the outside of said web and overlying said projection, said element being provided with a threaded hole registering with said opening, and a screw in said web opening threaded in said hole with its outer end engaging said member to hold the strip in place, the engaging surfaces of said locking element and projection being inclined rearwardly and outwardly to wedge said strip rearwardly against the front of the frame.

5. In a window, a frame provided with an inwardly opening channel for receiving the edge of a pane of glass, the web of said channel having an opening through it, a trim strip extending along the outside of the frame with its inner edge engaging the outer front edge of the frame, said strip having a longitudinally extending rib engaging the outer surface of the frame, the outer edge of said strip being provided with a rearwardly projecting flange opposite said web, the inner surface of said flange having a longitudinally extending rib opposite said opening provided with an inwardly and rearwardly inclined front surface, a locking member engaging the outside of said web and provided at its front end with a notch receiving said first-mentioned rib, said member being provided with a threaded hole registering with said web opening, and a screw in said web opening threaded in said hole with its outer end engaging the inclined front surface of said second-mentioned rib.

6. The combination with a wall having a window opening through it, of means secured to the wall of said opening and projecting into the opening, a frame having an outwardly projecting flange engaging the back side of said means, the frame having an inwardly opening channel 75 at the other side of said means for receiving the

edge of a pane of glass, the web of said channel having an opening through it, a trim strip extending along the outside of the frame with its inner edge engaging the front of the frame, said strip having a rearwardly extending member spaced from said web and engaging said means, said member being provided with an outwardly and forwardly inclined surface, said strip also having a projection engaging the outer surface of the frame, a locking element engaging the outside of said web and the front of said means and provided at its front with a notch receiving said projection which it overlaps, said locking element being provided with a threaded hole registering with said web opening, and a screw in said web opening threaded in said hole with its outer end engaging said inclined surface, whereby the locking element is held against said web and projection and said means, and said trim member is held against said means.

7. The combination with a wall having a window opening through it, of a channel whose web is secured to the wall of said opening and whose flanges project into the opening, a frame having outwardly projecting flanges engaging the back sides of said channel flanges, said frame having a portion projecting in front of the channel provided with an inwardly opening channel for receiving the edge of a pane of glass, the web of said frame channel having an opening through it, a locking element engaging said last-mentioned web and the front side of said wall channel, said element being provided with a threaded hole registering with said web opening, a screw in said web opening threaded in said hole with its outer end projecting therefrom, and a trim strip extending along the outside of the frame with its inner edge engaging the front of the frame, the outer edge of said strip being provided with a rearwardly projecting flange engaging the front of said wall channel, said strip having an inner projection provided with an inwardly and rearwardly inclined front surface, the projecting end of said screw bearing against said inclined surface to urge said trim flange rearwardly and to press said locking element against the frame, and said strip being provided with a rearward projection clamped between said locking element and frame.

50

8. In a window, an upper metal frame member provided with a plurality of transverse slots spaced lengthwise thereof, said member being provided in front of said slots with a downwardly opening channel for receiving the upper edge of a pane of glass, the web of said channel having an opening through it, vertical metal bars behind said channel, said bars being wider than the length of the slots and having their upper end portions reduced in width, said reduced end portions extending upwardly through said slots and being provided with lateral slots forming tongues above said frame member, said tongues being bent laterally to lock said bars in the frame member, a horizontal trim strip disposed above the frame with its lower edge overlapping the front of the frame, said strip having a rearwardly extending element above said web opening, and a screw in said opening with its upper end engaging said element to hold the trim strip in place.

9. In a window, a horizontal metal frame member provided with a plurality of transverse slots spaced lengthwise thereof, and vertical metal bars wider than the length of the slots and having end portions reduced in width extending outwardly through said slots, said reduced end portions being provided with lateral slots forming tongues outside said frame member, the outside of said frame member being provided beside said tongues with projections having inclined outer surfaces, and said tongues being bent laterally into engagement with said inclined surfaces to lock said bars and frame member together.
